CLAIM

The ornamental design for a digital camera, as shown and described.

DESCRIPTION

FIG. 1 is a perspective view of the top, front and right side of a digital camera showing my new design;

FIG. 2 is a perspective view of the top, rear and left side thereof;

FIG. 3 is a top plan view thereof;

FIG. 4 is a front elevational view thereof;

FIG. 5 is a left side elevational view thereof;

FIG. 6 is a right side elevational view thereof;

FIG. 7 is a rear elevational view thereof; and,

FIG. 8 is a bottom plan view thereof.

The elements shown in broken lines are for illustrative purposes only and form no part of the claimed design. Also, the dot-dash broken lines define the boundaries of the claimed portion and the non-claimed portion.
